Juan Gunfaus, Tarrasa, Barcelona, Spain, assignor to
Mery S.A., Barcelona, Spain

Filed Nov. 2, 1970, Ser. No. 25,783

Claims priority, application Spain May 8, 1970

Term of patent 14 years.

Int. Cl. D7—05

U.S. Cl. D49—29

FIG. 1

FIG. 2

FIG. 1 is a perspective view of a combined pail and mop wringer showing my new design; and

FIG. 2 is a perspective view showing the side and end not seen in FIG. 1.

I claim:

The ornamental design for a combined pail and mop wringer, substantially as shown.
